BALANCED FREQUENCY DETECTOR

Harold A. Wheeler, Great Neck, N. Y., assignor to
Hazeltine Corporation, a corporation of Delaware

Application March 29, 1941, Serial No. 385,801

7 Claims. (Cl. 250—27)

The present invention relates to an improved frequency-detector system for carrier-signal receivers and, particularly, to such a system of the balanced type. While the invention is of general application, it has particular utility as the frequency-detector system of a frequency-modulated carrier-signal receiver. The invention, therefore, will be described in connection with such a receiver wherein it is effective greatly to reduce the effect of received noise disturbances.

Frequency-modulation systems are subject to noise disturbances which generally produce incidentally an undesirable amplitude modulation of the carrier signal. While the amplitude-limiting system sometimes used in frequency-modulated receivers may reduce the effect of the noise disturbances, it cannot completely do so at all times and under all conditions of operation, especially when the received carrier signal is relatively weak. A carefully balanced frequency detector is a valuable adjunct to a limiter system in further reducing the effect of noise disturbances and is even more valuable if no limiter is used. A balanced frequency detector exhibits its greatest noise-reducing properties during the intervals when the carrier signal is unmodulated, at which time the noise is most noticeable, and particularly so when the carrier signal is of relatively low intensity.

The most common frequency-modulation detector of the prior art includes a slope filter comprising a transformer having a primary winding included in the anode circuit of a preceding repeater vacuum tube and having a center-tapped secondary winding, the center tap being coupled by a radio-frequency condenser to the high potential terminal of the primary winding. The terminals of the secondary winding are connected to a pair of rectifier devices each having an output load impedance and a common junction therefor. Such prior art detectors include an output circuit having the aforesaid load impedances, with suitable by-pass condensers, serially arranged therein, one terminal of the series circuit being conventionally grounded. The low potential terminal of the transformer primary winding is conventionally by-passed to ground through a condenser to provide a low-impedance path for carrier-signal currents around the anode space current supply source conventionally connected to this transformer terminal. Since the center tap of the secondary winding has an audio-frequency coupling to the common junction of the rectifier load imped-

ances, this coupling normally comprising a radio-frequency choke coil, the aforementioned radio-frequency condenser is effectively connected through the by-pass condenser across the load impedance of one of the rectifier devices, thereby to unequalize the impedance components of the rectifier load impedances. The radio-frequency coupling condenser ordinarily has a value large in comparison to the capacitance of the load impedances and the latter cannot, therefore, be well proportioned to avoid the unequalization thus effected. This results in the production of unequal voltages across the two load impedances at the higher audio frequencies which are predominant in undesired noise disturbances accompanying the carrier signal. The unequal noise voltages thus cannot be balanced out in the output circuit for this type of prior art frequency detector.

It is an object of the present invention, therefore, to provide an improved frequency-detector system of the balanced type which, while of general application, is especially suitable for use as the frequency-detector system of a frequency-modulated carrier-signal receiver and one which avoids one or more of the above-mentioned disadvantages and limitations of the prior art devices.

It is a further object of the invention to provide an improved frequency-detector system of simple circuit arrangement comprising a minimum number of circuit elements and one which has substantially zero response to spurious amplitude modulation and derives substantially zero output from a carrier signal having no frequency modulation, whereby the effect of noise disturbances is greatly reduced regardless of the strength of the received carrier signal.

In accordance with the invention, a balanced frequency detector comprises a slope filter including a transformer and means for deriving voltages equal to the sum and difference of voltages developed in the windings of the transformer by a carrier signal applied thereto. The detector includes a pair of rectifier devices so coupled to the slope filter as to have applied thereto individual ones of the sum and difference voltages, and a load network for each of the rectifier devices. The load networks have a common junction and the detector has an inherent impedance to ground tending to render the impedance components of said load network non-symmetrical relative to the common junction and means are included in one of the load networks for compensating the inherent capacitance to

render the impedance components symmetrical relative to the junction, whereby undesired transient amplitude disturbances of the applied carrier signal develop equal voltages of opposite polarities across the load networks with respect to the aforesaid common junction at the mean frequency of the applied carrier signal. The detector additionally includes an output circuit coupled to the load networks for deriving a voltage equal to the difference of the voltages developed across the load networks.

For a better understanding of the present invention, together with other and further objects thereof, reference is had to the following description taken in connection with the accompanying drawing, and its scope will be pointed out in the appended claims.

Referring now to the drawing, Fig. 1 is a circuit diagram, partly schematic, of a complete frequency-modulated carrier-signal receiver of the superheterodyne type embodying the invention; Fig. 2 represents a suitable slope-filter transformer construction for the Fig. 1 circuit; Fig. 3 is a circuit diagram of a portion of a carrier-signal receiver embodying a modified form of the invention; and Fig. 4 is a slope-filter transformer construction suitable for the circuit of Fig. 3.

Referring now more particularly to Fig. 1, there is represented schematically a complete frequency-modulated carrier-signal receiver of the superheterodyne type and of conventional design embodying the present invention in a preferred form. In general, the receiver includes a radio-frequency amplifier 10 having its input circuit connected to an antenna system 11, 12 and having its output connected to an oscillator-modulator 13. Connected in cascade with the oscillator-modulator, in the order named, are an intermediate-frequency amplifier 14 of one or more stages, a frequency detector 15 more fully described hereinafter, an audio-frequency amplifier 16 of one or more stages, and a sound reproducer 17. An automatic amplification control or A. V. C. rectifier 9 also is connected to the intermediate-frequency amplifier 14 and the output of the rectifier is applied to the input circuits of one or more of the tubes of the radio-frequency amplifier 10, the oscillator-modulator 13, and the intermediate-frequency amplifier 14 in conventional manner.

It will be understood that the various units just described may, with the exception of the frequency detector 15, be of a conventional construction and operation, the details of which are known in the art, rendering further detailed description thereof unnecessary. Considering briefly the operation of the receiver as a whole, and neglecting for the moment the detailed operation of the frequency detector 15 presently to be described, a desired frequency-modulated carrier signal is selected and amplified by the radio-frequency amplifier 10, converted to a frequency-modulated intermediate-frequency carrier signal in the oscillator-modulator 13, amplified in intermediate-frequency amplifier 14, and detected by the frequency detector 15, thereby to derive the audio-frequency modulation components. The audio-frequency components are, in turn, amplified in the audio-frequency amplifier 16 and are reproduced by the sound reproducer 17 in a conventional manner. The intermediate-frequency carrier signals also are applied to the automatic amplification control or A. V. C. rectifier 9 to derive an automatic control or A. V. C.

bias. This bias is effective to control the amplification of one or more of the units 10, 13, and 14 to maintain the signal input to the detector 15 within a relatively narrow range for a wide range of received signal intensities.

Referring now more particularly to the portion of the system embodying the present invention, the frequency detector 15 includes a slope filter 18 comprising a transformer having a first winding 19 included in the output circuit of the intermediate-frequency amplifier 14, a second winding 20 coupled to the first winding 19, and a center-tapped third winding 21 coupled to winding 20 but substantially uncoupled to winding 19 so that the second winding 20 provides substantially the entire energy transfer from the first winding 19 to the third winding 21. The second and third windings 20, 21 of the slope-filter transformer are tuned by the respective condensers 22, 23 to the mean frequency of the intermediate-frequency modulated-carrier signal of the receiver. The detector 15 includes means for deriving voltages equal to the sum and difference of the voltages developed in the windings 20, 21 of the slope-filter transformer comprising a connection between the center tap of the transformer winding 21 and a terminal of the transformer winding 20, a pair of rectifier devices 26, 27, which are individually connected with like polarity between the terminals of winding 21 and the other terminal of winding 20 so as to have applied thereto individual ones of said sum and difference voltages, and respective load networks 28, 29. The load networks 28 and 29 include similar resistors 30, 32, respectively, and shunt-connected condensers 31, 33, respectively. The frequency detector 15 is provided with an output circuit comprising an output terminal 34 and a grounded output terminal 35 with the load networks 28, 29 included in series therebetween to derive a voltage equal to the difference of the voltages developed across the load networks. As thus arranged, the load networks 28, 29 have a common junction 36 which is connected to one terminal of the transformer winding 20 of the slope filter 18. The circuit to the common junction 36 has an inherent capacitance to ground, represented by the broken-line condenser 37, which is effectively in shunt to the condenser 33 of the load network 29 and tends undesirably to render unsymmetrical the impedance components of the load circuit of the frequency detector.

Considering now the operation of the frequency-detector system just described, the detector is initially adjusted for balanced operation by adjusting the condenser 33 to such value that the sum of the capacitance of the condenser 33 and the inherent capacitance of the condenser 37 is equal to the capacitance of the condenser 31. When this is done, the sums of all like physical and inherent impedance components of the detector are symmetrical with respect to the common junction 36. The adjustable condenser 33 thus comprises means included in one of the load networks for compensating the inherent capacitance at the common junction 36 to equalize the total capacitance across the load networks 28, 29, or to render the impedance components symmetrical relative to the junction 36. The slope filter 18 derives from the intermediate-frequency carrier signal applied thereto two voltages varying in magnitude in opposite senses with the frequency of the carrier signal. These voltages, the sum and difference voltages of the transformer

windings of the slope filter 18, are applied to individual ones of the rectifier devices 26, 27 to develop across the load networks 28, 29 unidirectional voltages of opposite polarities with respect to the common junction 36 and of magnitude varying in opposite senses with the frequency of the carrier signal. The unidirectional voltages thus developed are combined in the output circuit of the frequency detector 15 to derive a modulation voltage equal to the difference of the voltages developed across the load networks 28, 29. The modulation voltage is applied to the input of the audio-frequency amplifier 16 for amplification therein in conventional manner. Since all impedance components of the frequency detector are symmetrical with respect to the common junction 36, as pointed out above, undesired transient amplitude disturbances of the applied intermediate-frequency carrier signal develop equal transient unidirectional voltages of opposite polarities across the load networks 28, 29 at the mean frequency of the applied carrier signal. These transient voltages balance out in the output circuit of the detector 15 and consequently are not reproduced by the sound reproducer 17.

Fig. 2 illustrates a suitable construction for the transformer of the slope filter 18 in the Fig. 1 embodiment of the invention. The first winding 19 is a multilayer winding relatively closely coupled to the second winding 20, which is of the single-layer winding type. The third winding 21 is also a multilayer winding and is relatively loosely coupled to the winding 20 in order to reduce the coupling between windings 19 and 21 to a minimum. The three windings are supported on a common tubular insulating member 38 and the transformer is enclosed within a shield 40.

As illustrative of a specific embodiment of the invention, the following circuit constants are given for an embodiment of the invention of the type shown in Fig. 1:

	Millihenries
Inductance of transformer winding 19	48
Inductance of transformer winding 20	37
Inductance of transformer winding 21	43
External diameter of support 38 inch	0.75
Spacing between windings 19 and 20	0.0625
Spacing between transformer windings 20 and 21	0.343
Length of winding 20	0.375
Rectifier devices 26, 27	Type 7A6
Resistors 30 and 32	ohms 220,000
Condenser 31	micro-microfarads 500
Condenser 33	do 100-500

Fig. 3 is a circuit diagram of a portion of a complete signal-carrier receiver and represents a modified form of the detector system which is essentially similar to that of the Fig. 1 arrangement, similar circuit elements being designated by similar reference characters. This modification of the invention differs from that shown in Fig. 1 in that the slope filter 18 includes two separate transformers 41 and 42, the transformer 41 comprising a primary winding 19' and a secondary winding 43, while the transformer 42 comprises the windings 20 and 21 which are coupled as in Fig. 1 to derive the sum and difference voltages applied to the rectifier devices 26 and 27. The transformer 42 is coupled to the transformer 41 only by a link circuit comprising the windings 20, 43 and the condenser 22. This

modification of the invention differs also from that of Fig. 1 in that the inherent capacitance 37 of the circuit of the common junction 36 is compensated by an adjustable condenser 39 connected in shunt to the condenser 31 of the load network 28. The corresponding circuit elements of the load networks 28, 29 have equal values of resistance and capacitance, and the condenser 39 is initially adjusted, in balancing the frequency detector 15, to a value of capacitance equal to that of the inherent capacitance 37, whereby the frequency detector has physical and inherent impedance components symmetrical with respect to the common junction 36. The operation of this modification of the invention is essentially similar to that of Fig. 1, the particular form of slope-filter transformer arrangement ensuring minimum coupling between the transformer windings 19 and 21 and will, therefore, not be repeated.

Fig. 4 illustrates a suitable construction for the transformer 42 of the slope filter 18 in the Fig. 3 modification of the invention. The transformer winding 21, which is shown in schematic form, is symmetrically disposed on the center of an insulating winding form 38 and the two halves of the winding 21 are bifilar-wound. The transformer winding 20 is also wound in two sections, one on each side of the winding 21. The two sections of the winding 20 are wound in opposite directions and are connected in parallel with aiding mutual inductance, as shown. This transformer construction is of the type disclosed by applicant in the proceedings of the Institute of Radio Engineers, April 1928, pages 476-481.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A balanced frequency detector comprising, a slope filter including a transformer and means for deriving voltages equal to the sum and difference of voltages developed in the windings of said transformer by a carrier signal applied thereto, a pair of rectifier devices so coupled to said slope filter as to have applied thereto individual ones of said sum and difference voltages, a load network for each of said devices, said load networks having a common junction and said detector having an inherent capacitance to ground tending to render the impedance components of said load networks non-symmetrical relative to said junction, means included in one of said load networks for compensating said inherent capacitance to render said impedance components symmetrical relative to said junction whereby undesired transient amplitude disturbances of said applied carrier signal develop equal voltages of opposite polarities across said load networks with respect to said common junction at the mean frequency of said applied carrier signal, and an output circuit coupled to said load networks for deriving a voltage equal to the difference of the voltages developed across said load networks.

2. A balanced frequency detector comprising, an input circuit adapted to have a carrier signal applied thereto, a slope filter including a transformer having a first winding coupled to said in-

put circuit and having second and third coupled windings, one of said second and third windings being coupled to said first winding and said second and third windings being connected to derive voltages equal to the sum and difference of voltages developed therein by said applied carrier signal, a pair of rectifier devices so coupled to said slope filter as to have applied thereto individual ones of said sum and difference voltages, a load network for each of said devices, said load networks having a common junction and said detector having an inherent capacitance to ground tending to render the impedance components of said load networks non-symmetrical relative to said junction, means included in one of said load networks for compensating said inherent capacitance to render said impedance components symmetrical relative to said junction whereby undesired transient amplitude disturbances of said applied carrier signal develop equal voltages of opposite polarities across said load networks with respect to said common junction at the mean frequency of said applied carrier signal, and an output circuit coupled to said load networks for deriving a voltage equal to the difference of the voltages developed across said load networks.

3. A balanced frequency detector comprising, an input circuit adapted to have a carrier signal applied thereto, a slope filter including a transformer having a first winding coupled to said input circuit and having second and third windings coupled to derive voltages equal to the sum and difference of voltages developed therein by said carrier signal, said second winding providing substantially the entire energy transfer from said first winding to said third winding, a pair of rectifier devices so coupled to said slope filter as to have applied thereto individual ones of said sum and difference voltages, a load network for each of said devices, said load networks having a common junction and said detector having an inherent capacitance to ground tending to render the impedance components of said load networks non-symmetrical relative to said junction, means included in one of said load networks for compensating said inherent capacitance to render said impedance components symmetrical relative to said junction whereby undesired transient amplitude disturbances of said applied carrier signal develop equal voltages of opposite polarities across said load networks with respect to said common junction at the mean frequency of said applied carrier signal, and an output circuit coupled to said load networks for deriving a voltage equal to the difference of the voltages developed across said load networks.

4. A balanced frequency detector comprising, a slope filter including a transformer and means for deriving voltages equal to the sum and difference of voltages developed in the windings of said transformer by a carrier signal applied thereto, a pair of rectifier devices so coupled to said slope filter as to have applied thereto individual ones of said sum and difference voltages, a load network for each of said devices, said rectifier devices being connected in said rectifier systems with like polarity with respect to said slope filter, said load networks having a common junction and said detector having an inherent capacitance to ground tending to render the impedance components of said load networks non-symmetrical relative to said junction, means included in one of said load networks for compensating said inherent capacitance to render said impedance

components symmetrical relative to said junction whereby undesired transient amplitude disturbances of said applied carrier signal develop equal voltages of opposite polarities across said load networks with respect to said common junction at the mean frequency of said applied carrier signal, and an output circuit coupled to said load networks for deriving a voltage equal to the difference of the voltages developed across said load networks.

5. A balanced frequency detector comprising, a slope filter including a transformer and means for deriving voltages equal to the sum and difference of voltages developed in the windings of said transformer by a carrier signal applied thereto, a pair of rectifier devices so coupled to said slope filter as to have applied thereto individual ones of said sum and difference voltages, a load network for each of said devices, said load networks having a common junction, and said detector having an inherent capacitance to ground effectively in shunt relation to one of said load networks tending to render the impedance components of said networks non-symmetrical relative to said junction, means included in said one load network to render the sums of all physical and inherent impedance components of the frequency detector symmetrical with respect to said common junction, whereby undesired transient amplitude disturbances of said applied carrier signal develop equal voltages of opposite polarities across said load networks with respect to said common junction at the mean frequency of said applied carrier signal, and an output circuit coupled to said load networks for deriving a voltage equal to the difference of the voltages developed across said load networks.

6. A balanced frequency detector comprising, a slope filter including a transformer and means for deriving voltages equal to the sum and difference of voltages developed in the windings of said transformer by a carrier signal applied thereto, a pair of rectifier devices so coupled to said slope filter as to have applied thereto individual ones of said sum and difference voltages, a load network for each of said devices, said load networks having a common junction, an output circuit coupled to said load networks and having a grounded terminal for deriving a voltage equal to the difference of the voltages developed across said load networks, the circuit to said common junction having inherent capacitance to ground which tends undesirably to render unsymmetrical the impedance components of said load networks with respect to said junction, and means for compensating said inherent capacitance to equalize the total capacitance across said load networks, whereby undesired transient amplitude disturbances of said applied carrier signal develop equal voltages of opposite polarities across said load networks with respect to said common junction at the mean frequency of said applied carrier signal.

7. A balanced frequency detector comprising, a slope filter including a transformer and means for deriving voltages equal to the sum and difference of voltages developed in the windings of said transformer by a carrier signal applied thereto, a pair of rectifier devices so coupled to said slope filter as to have applied thereto individual ones of said sum and difference voltages, a load network for each of said devices, said load networks having a common junction, an output circuit coupled to said load networks and having a grounded terminal for deriving a

voltage equal to the difference of the voltages developed across said load networks, the circuit to said common junction having inherent capacitance to ground which tends undesirably to render unsymmetrical the impedance components of said load networks with respect to said junction, and an adjustable condenser connected across one of said load networks for compensating said inherent capacitance to equalize the

total capacitance across said load networks, whereby undesired transient amplitude disturbances of said applied carrier signal develop equal voltages of opposite polarities across said load networks with respect to said common junction at the mean frequency of said applied carrier signal.

HAROLD A. WHEELER.
